UNITED STATES PATENT OFFICE.

EDWARD G. GROSS, OF COLUMBUS, GEORGIA, ASSIGNOR OF ONE-HALF TO F. F. GAINES,
OF WASHINGTON, DISTRICT OF COLUMBIA.

EXHAUST-PIPE FOR LOCOMOTIVES.

1,277,407.

Specification of Letters Patent. Patented Sept. 3, 1918.

Application filed August 30, 1917. Serial No. 188,973.

To all whom it may concern:

Be it known that I, EDWARD G. GROSS, a citizen of the United States, residing at Columbus, in the county of Muscogee and 5 State of Georgia, have invented new and useful Improvements in Exhaust-Pipes for Locomotives; and I do declare the following to be a full, clear, and exact description of the invention, such as will enable others 10 skilled in the art to which it appertains to make and use the same.

My invention relates to that class of devices which are positioned in the smoke boxes of locomotives for so directing the exhaust steam from the cylinders as to create 15 the required draft through the boiler tubes and fire box.

One object of the invention is to reduce the back pressure in the cylinders by increasing 20 the area of the several steam passages, thus giving the locomotive all the tractive power available.

A further object of the device is to provide 25 an exhaust steam pipe which will spread the steam before releasing it, so that the petticoat pipe and smoke stack are completely and instantly filled, thus forming a more perfect and constant vacuum in the smoke box.

30 Yet another object is to create an exhaust pipe which will produce a lighter but more continuous draft on the fire in the fire box, on account of the correct passage of the steam through the exhaust pipe and smoke 35 stack.

With the foregoing general objects in view, the invention resides in certain novel features of construction and unique combinations of parts to be hereinafter fully 40 described and claimed, the descriptive matter being supplemented by the accompanying drawings which form a part of this specification and in which:

Figure 1 is a vertical longitudinal section 45 of the smoke box of a locomotive, showing a side elevation of the invention applied;

Fig. 2 is a vertical transverse section on the plane of the line 2—2 of Fig. 1;

Fig. 3 is a top plan view of the improved 50 exhaust pipe;

Fig. 4 is a vertical section thereof on the plane of the line 4—4 of Fig. 3; and

Figs. 5 and 6 are respectively vertical and

horizontal sections on the planes indicated 55 by the lines 5—5 and 6—6 of Fig. 4.

In the drawings above briefly described, the numeral 1 designates the usual smoke box at the front end of a locomotive, whereas 60 2 has reference to a smoke stack from which the usual or any preferred type of apron or petticoat pipe 3 depends into the smoke box, the lower end of said apron or petticoat pipe being outwardly flared as indicated at 4 and positioned above the improved 65 exhaust steam pipe 5.

The pipe 5 is formed of a comparatively flat body having an outwardly projecting flange 6 at its lower end and gradually increasing in width toward its upper end, said 70 body having a longitudinal cavity 7 formed therein which opens through said upper end, as clearly shown in the drawings.

The lower end of the body 5 passes through an opening in the bottom of the 75 smoke box, and the flange 6 is secured to the engine in the usual or any suitable manner. This means is preferable, but other methods may be followed for securing the device in place, should occasion demand. 80

A pair of exhaust passages 8, are formed in the body of the improved pipe, along the opposite edges of the latter and adjacent opposite sides of the cavity 7, the lower ends of said passages being adapted for communication with the usual exhaust ports which lead from the cylinders of the locomotive. The upper ends of the passages 8 are directed downwardly as indicated at 9 so that they discharge into the cavity 7 on lines 90 which converge toward the bottom of said cavity. By this arrangement, the exhaust steam is directed downwardly into the cavity 7 which spreads the volume of steam and gives it the proper contour before it is released into the petticoat pipe or apron 3 and the stack 2.

This action also reduces the velocity of the steam causing a long and continuous draft through the boiler tubes, which means 100 a noticeable saving in fuel, yet the power of the engine is not decreased to any extent whatever, since the draft is more continuous than when employing the usual types of exhaust pipes.

Another feature which renders the device 105 highly efficient for the purposes intended,

is the comparatively large transverse area of the passages 8. These passages are of noticeably greater dimensions than those usually employed and thus there is but slight 5 checking of the exhaust steam passing therethrough, with the result that the action of the pistons in the cylinders is not appreciably impaired. Both passages 8 preferably decrease slightly in size at the point 10 of discharge into the cavity 7, and although this construction has proven highly satisfactory, the actual manufacture of the device may dictate that other proportions be followed. I do not therefore wish to be 15 restricted to any such unimportant details of construction.

A blower port 10 is formed transversely through the body of the pipe or around the upper end of the cavity 7, and is adapted 20 to discharge into the Petticoat pipe and smoke stack, said port being adapted for connection, by any suitable means, not shown, with a fluid pressure blast to create the required draft when the engine is not 25 working steam. Also, although it does not add to the operation of the device, a horizontal flange 11, or lugs spaced at intervals, surround the improved pipe as shown, it being intended that the usual horizontal 30 screen (not shown) shall be attached to said flange or lugs, it being the office of this screen to prevent the escape of sparks and cinders through the smoke stack with the exhaust steam.

35 From the foregoing, taken in connection with the accompanying drawings, it will be obvious that although the improved exhaust steam pipe is of comparatively simple and inexpensive construction, it will be highly 40 efficient and durable. Since probably the best results are obtained from the specific construction shown and described, such construction constitutes the preferred form of the device. I wish it understood, however, 45 that within the scope of the invention as claimed numerous minor changes may be made.

I claim:—

50 1. An exhaust pipe for locomotives, comprising a one-piece comparatively flat cast

metal body disposed in a vertical plane and increasing in width toward its upper end but being of substantially uniform thickness, said body having a central vertical cavity opening through its upper end, a pair of 55 upwardly diverging exhaust passages between said cavity and the edges of said body, the lower ends of said passages opening through the narrow lower end of said body and the upper ends of said passages 60 being curved downwardly and inwardly and discharging into opposite sides of said cavity on downwardly converging lines, said downwardly and inwardly extending passage ends decreasing gradually in size toward 65 their delivery terminals, laterally projecting means integral with the narrow lower end of said body for securing it to the smoke box of the locomotive, and laterally extending means above said first named means for 70 the attachment of the usual screen.

2. An exhaust pipe for locomotives, comprising a one-piece comparatively flat cast metal body disposed in a vertical plane and increasing in width toward its upper end but 75 being of substantially uniform thickness, said body having a central vertical cavity opening through its upper end, a pair of upwardly diverging exhaust passages between said cavity and the edges of said body, the lower ends of said passages opening 80 through the narrow lower end of said body and the upper ends of said passages being curved downwardly and inwardly and discharging into opposite sides of said cavity on 85 downwardly converging lines, an annular passage formed in said body around the upper end of said cavity, means for admitting fluid under pressure to said annular passage, and an annular series of outlets from 90 said annular passage opening through the upper end of said body around said cavity.

In testimony whereof I have hereunto set my hand in the presence of two subscribing witnesses.

EDWARD G. GROSS.
